UNITED STATES PATENT OFFICE.

CHARLES W. GREEN, OF MILLBURN, NEW JERSEY, ASSIGNOR, BY MESNE ASSIGNMENTS, TO WESTERN ELECTRIC COMPANY, INCORPORATED, A CORPORATION OF NEW YORK.

TRANSMISSION REGULATION.

Application filed January 31, 1925. Serial No. 5,969.

To all whom it may concern:

Be it known that I, CHARLES W. GREEN, a citizen of the United States of America, residing at Millburn, in the county of Essex 5 and State of New Jersey, have invented certain new and useful Improvements in Transmission Regulations, of which the following is a full, clear, concise, and exact description.

10 This invention relates to transmission regulation and is particularly adapted for use in carrier current signaling systems.

An object of the invention is to maintain 15 the transmission efficiency of a carrier signaling system constant under varying conditions.

Another object of the invention is to increase the sensitivity of transmission regulating systems.

20 The invention is particularly applicable to signaling systems employing fairly high frequencies in which, as is well known, the transmission characteristics of the transmission medium are subject to variations which 25 render it difficult to maintain uniform signaling conditions.

Changes in the attenuation of the transmission medium of a system of this type produce corresponding variations in the overall 30 transmission equivalent of the system, and result in large fluctuations in the volume of a telephone or other message being transmitted.

In order to overcome the effects of transmission variations in such systems, it is common practice to subject a pilot frequency to the same conditions as those affecting the signaling frequencies, and to utilize the pilot frequency so transmitted to adjust the transmission at repeaters or other points in the system. Such a system is shown, for example, in Patent No. 1,511,013 to H. A. Affel, 40 issued October 7, 1924.

According to a feature of the present invention a pilot frequency is transmitted between the terminals of a multiplex signaling system, and the second harmonic of this frequency is utilized to operate an automatic compensator in the transmission line at a 45 repeater or other point in the system.

In the preferred embodiment of the invention the second harmonic of the pilot frequency is picked up in the common output lead of a push-pull repeater amplifier

and utilized to control a potentiometer in 55 the repeater input circuit.

Increased sensitivity is obtained by using the second harmonic of the pilot frequency in accordance with the invention, as the amplitude of the second harmonic will vary as 60 the square of the amplitude of the pilot frequency.

The invention will be described as applied to a repeater for use in multiplex carrier current telephone or telegraph systems, but 65 it is to be understood that it may also be applied to other places in the system than at repeater points, and to various types of systems other than multiplex carrier signaling systems.

70 The various features and advantages of the invention will appear from the following description taken in connection with the accompanying drawing, which shows a circuit diagram illustrating the invention.

The drawing shows a one-way repeater 75 adapted to couple two transmission line sections W and E. The signaling waves incoming at the repeater from line section W are amplified in the repeater and the amplified waves are delivered to line section E.

The repeater may be of any well known type such as the balanced amplifier described in connection with Fig. 21 of an article entitled "Carrier current telephony and telegraphy" by Messrs. Colpitts and Blackwell, 80 published in the Transactions of the American Institute of Electrical Engineers, volume 40, 1921.

85 As illustrated, the balanced amplifier comprises a pair of three-element electron discharge tubes 1 and 2. Parallel input circuits having a common path 3 and individual paths 4 and 5 are connected between the filaments and grids of the two tubes. The line section W is coupled to the input circuits through a transformer 6. Parallel output circuits comprising a common path 7 and individual paths 8 and 9 are connected between the filaments and plates of the tubes, 90 the output circuits being coupled to line section E through a transformer 10.

95 In addition to the signaling frequencies which are adapted to be amplified in the repeater, a pilot current is also impressed upon the line section W in the usual manner at the distant terminal, not shown. The second harmonic of the pilot frequency is 100 105

picked up across a resistance 11 in the common output path 7 where the level of second order modulation products and second harmonics is highest. The second harmonic is selected to the exclusion of all other frequencies by means of a selective circuit 12, which may be either a tuned circuit or a band filter of well-known type. The selected harmonic of the pilot frequency is then amplified in an amplifier 13 and rectified by means of a rectifier 14 of any well known type. A voltmeter relay 15 in the output of the rectifier 14 is controlled by the rectifier currents.

15 The voltmeter relay 15 may be arranged with its armature so biased that the direct current flowing in the output circuit of the rectifier 14 when the transmission efficiency of line section W is normal, will be just sufficient to hold the armature at a neutral point against the tension of the biasing means. An increase or decrease in the direct current in response to an increase or decrease in the efficiency of line section W will, therefore, result in shifting the armature to one or the other of its contacts.

In order to adjust the transmission efficiency of the repeater, a potentiometer 16 is included in the line section W on the input side of the repeater. This potentiometer may be adjusted by means of an arm 17 which may be rotated by a motor 18. The motor 18 may be energized from the power mains 19 and its circuits are controlled by means of relays 20 and 21, so that when either of these relays is operated the armature circuit is closed, and when one of the relays is operated the field circuit is completed in one direction while when the other relay is operated the field circuit is completed in the opposite direction.

Relays 20 and 21 are controlled by the contacts of the voltmeter relay 15 so that if the armature of the relay 15 is shifted to one contact, the motor 18 will rotate in one direction and adjust the potentiometer to increase the transmission, while if the armature is shifted to the other contact of relay 15, the motor rotates in the opposite direction and adjusts the potentiometer to decrease the transmission.

In describing the operation of the transmission regulating system, let it be assumed that the line section W increases in attenuation so that the output level of the repeater amplifier is correspondingly decreased. Under such conditions the pilot current incoming from line section W is attenuated more than the normal amount, and the level of the second harmonic of the pilot frequency in the common path 7 of the repeater amplifier is correspondingly decreased. Current in the output of rectifier 14 is therefore decreased and the voltmeter relay 15 will be shifted to close one

of its contacts, say the left hand contact, thereby energizing the relay 21. The operation of relay 21 completes the field and armature circuits of the motor 18 to cause the motor to rotate in one direction and adjust the potentiometer 16 to gradually increase the gain of the amplifier until a condition is reached such that the amplitude of the second harmonic of the pilot frequency will be sufficient to produce a rectified current in the rectifier 14 of such value as to again shift the armature of the voltmeter relay 15 to a neutral position. When such a condition has been reached the operation of the motor 18 will cease, the change in the transmission of the line section W having been compensated for by the increased gain of the amplifier.

If the transmission efficiency of the line section W is increased, the pilot current incoming at the repeater is increased in amplitude, and the level of the second harmonic of the pilot frequency in the common path 7 is correspondingly increased. This causes a greater direct current to flow through the voltmeter relay 15, shifting the armature to the right hand contact to energize the relay 20. The operation of the relay 20 causes the motor 18 to rotate in the opposite direction and adjust the potentiometer 16 so that the gain of the repeater amplifier is gradually decreased. This results in a gradual decrease in the amplitude of the pilot frequency, and hence of the level of the second harmonic of the pilot frequency, until a point is reached where the direct current flowing through the voltmeter relay 15 will be reduced to its normal value, so that the armature of relay 15 is shifted to neutral and the motor 18 stops rotating.

It will be seen from the above that increased sensitivity is obtained by using the second harmonic of the pilot frequency to control the gain and level of the repeater amplifier, as the amplitude of the second harmonic will vary as the square of the amplitude of the pilot frequency. Hence, this regulating system serves to compensate for very small changes in the transmission of the system, and the system is automatically adjusted to operate at its maximum efficiency at all times.

The invention set forth herein is, of course, susceptible of various other modifications and adaptations not specifically referred to, but included within the scope of the appended claims.

What is claimed is:

1. The method of transmission regulation which comprises transmitting a wave over a variable transmission medium, producing a harmonic of said wave, and utilizing said harmonic to control the transmission efficiency of said medium.

2. The method of regulating the transmission of a variable transmission medium over which carrier waves are transmitted, which comprises selecting the second harmonic of one of said waves, and controlling an element in said transmission medium in accordance with the amplitude of said harmonic. 5
3. The method of regulating the transmission of a variable transmission medium over which carrier waves are transmitted which comprises selecting the second harmonic of one of said waves, rectifying the selected harmonic, and controlling an element in said transmission medium in accordance with the rectified current. 10
4. In a signaling system in which a plurality of signaling waves are simultaneously transmitted over a variable conducting path, the method of maintaining a constant transmission equivalent which consists in subjecting a pilot wave to substantially the same conditions causing attenuation as those affecting the signaling waves, deriving a harmonic of said pilot wave, and controlling an element in said conducting path in accordance with the amplitude of said harmonic. 20
5. In a signaling system in which a plurality of signaling waves are simultaneously transmitted over a variable conducting path, the method of maintaining a constant transmission equivalent which consists in subjecting a pilot wave to substantially the same conditions causing attenuation as those affecting the signaling waves, deriving the second harmonic of said pilot wave, rectifying said harmonic, and controlling an element in said conducting path in accordance with the rectified current. 30
6. In a system of transmission regulation, a variable transmission medium over which carrier waves are transmitted, means to derive a harmonic of one of said waves, and means controlled by said harmonic to regulate the transmission of said medium. 40
7. In a system of transmission regulation, a variable transmission medium over which a pilot wave is transmitted, means to derive the second harmonic frequency of said pilot wave, and means controlled by said harmonic frequency to regulate the transmission of said medium. 50
8. In a system of transmission regulation, a variable transmission line over which a pilot wave and signaling waves are transmitted, a potentiometer in said transmission line, means to derive a harmonic frequency of said pilot wave, and means controlled by
- said harmonic frequency to adjust said potentiometer when the transmission of said line departs from normal. 60
9. In a system of transmission regulation, a variable transmission line over which a pilot wave and signaling waves may be simultaneously transmitted, an amplifier associated with said line, means to derive a harmonic frequency of said pilot wave, and means controlled by said harmonic frequency to adjust the gain of said amplifier. 65
10. In a system of transmission regulation, a variable transmission line over which a pilot wave and signaling waves may be simultaneously transmitted, a repeater associated with said line, a potentiometer in the input circuit of said repeater, means to derive a harmonic frequency of said pilot wave, and means controlled by said harmonic frequency to adjust said potentiometer when the transmission of said line departs from normal. 70
11. In a system of transmission regulation, a variable transmission line over which a pilot wave and signaling waves may be simultaneously transmitted, a repeater comprising a balanced amplifier associated with said line, a potentiometer in the input circuit of said amplifier, means in the output circuit of said amplifier to select a harmonic frequency of said pilot wave produced by modulation in said amplifier, and means controlled by the selected harmonic frequency to adjust said potentiometer when the transmission of said line departs from normal. 75
12. In a system of transmission regulation, a variable transmission line over which a pilot wave and signaling waves may be simultaneously transmitted, a repeater comprising a balanced amplifier associated with said line, a potentiometer in the input circuit of said repeater, a selective circuit for transmitting the second harmonic frequency of the pilot wave produced by modulation in the output of said balanced amplifier, means to produce from said selected harmonic frequency a direct current whose amplitude depends upon the transmission conditions to which the pilot wave has been subjected, and means controlled by said direct current to adjust said potentiometer to compensate for the change in transmission efficiency of said transmission line. 95

In witness whereof I hereunto subscribe my name this 28th day of January A. D., 1925.

CHARLES W. GREEN.
